UNITED STATES PATENT OFFICE.

CLAY H. ESTES, OF CINCINNATI, OHIO.

LANTERN.

1,321,192.

Specification of Letters Patent.

Patented Nov. 11, 1919.

Application filed March 3, 1919. Serial No. 280,353.

To all whom it may concern:

Be it known that I, CLAY H. ESTES, a citizen of the United States, residing at Cincinnati, in the county of Hamilton and 5 State of Ohio, have invented certain new and useful Improvements in Lanterns, of which the following is a specification, reference being had to the accompanying drawings.

10 This invention relates to certain improvements in lanterns, and has relation more particularly to a device of this general character of a type especially designed and adapted for use by railroad employees, and 15 it is an object of the invention to provide a novel and improved lantern of this kind embodying a supplemental color screen removable into and out of position relative to the burner of the lantern so that the light 20 rays emitted from the lantern may be changed as to color.

A further object of the invention is to 25 provide a novel and improved lantern of this type including a cylindrical base in which the burner is arranged together with a supplemental color screen movable into or out of the base and wherein said screen has coacting therewith means for maintaining the burner in applied position within the 30 base.

The invention consists in the details of construction and in the combination and arrangement of my improved lantern whereby certain important advantages are attained 35 and the device rendered simpler, less expensive and otherwise more convenient and advantageous for use, as will be hereinafter more fully set forth.

The novel features of my invention will 40 hereinafter be definitely claimed.

In order that my invention may be the better understood, I will now proceed to describe the same with reference to the accompanying drawings, wherein:

45 Figure 1 is a view in elevation illustrating a lantern constructed in accordance with an embodiment of my invention.

Fig. 2 is an enlarged fragmentary vertical sectional view taken through the lower 50 portion of the lantern as herein included, certain of the parts being omitted.

Fig. 3 is a view in top plan of the oil reservoir as herein disclosed, and

55 Fig. 4 is an enlarged top plan view of the supporting member for the color screen.

As disclosed in the accompanying draw-

ings, F denotes a lantern frame comprising vertically arranged standards 1 in radial relation and formed of inwardly extending knees 2. The standards 1 are connected above the knees 2 by the wires 3 while the opposite extremities of the standards 1 are engaged with the rings 4. Coacting with the upper ring 4 in a well known manner is a cover C.

60 Between the knees 2 and secured thereto is the base B preferably cylindrical in form and having its lower marginal portion defined by an inwardly directed flange 5 while the upper marginal portion of the base B is provided with the outwardly directed flanged shoulder 6 with which the globe or chimney G is engaged in a conventional manner.

65 7 denotes an oil reservoir insertible within the base B and of a maximum diameter less than the mean diameter of said base, and said reservoir is permanently fixed at its base with a disk D snugly fitting within the base B and resting upon the flange 5 whereby the reservoir 7 is properly supported 75 within the base B. The marginal portion of the disk D is defined by an upstanding flange 8 while the extended portion of the disk D is provided with the openings 9 to facilitate the requisite draft. To further 80 facilitate the draft and to accommodate sufficient air to support combustion the side wall of the reservoir 7 is provided with longitudinally disposed corrugations 10 with the openings 9 adjacent the low points of the 85 corrugations.

90 The reservoir 7 when applied has its upper end preferably terminating below the shoulder 6 and coacting with said upper end of the reservoir 7 is a burner 11 of a conventional type.

95 M denotes an annular member snugly fitting within the base B and surrounding the reservoir 7 and the inner marginal portion of said member M is defined by the upstanding flange 12. The member M serves as a holder for the screen S of suitable transparent material and preferably red in color for a purpose which will be hereinafter more particularly defined.

100 At preferably diametrically opposed points the member M has depending therefrom the lugs or blocks 14 with which are engaged the outwardly directed finger pieces 15. Each of the finger pieces 15 is 110 directed through a vertical slot 16 formed in the wall of the base B and open at its top.

The opposite end portions of the slot 16 are offset laterally or provided with bayonet extensions, as indicated at 17, so that upon partial rotation of the member M said member 5 may be locked in its lowermost position and whereby said member M is normally held against displacement when at the limit of its upward movement.

Suitably secured to the under surface of 10 the member M is an end portion of a spiral spring 18 and which spring encircles the reservoir 7 and engages the extended portion of the disk D. The spring 18 is of an expandable type so that the same constantly urges the 15 disk D toward the flange 5 of the base B so that the reservoir 7 is effectively maintained in applied position. However, the reservoir 7 can be readily removed after the member M and the spring 18 carried thereby 20 has been withdrawn from applied position within the base B.

The spring 18 also operates to facilitate the elevation of the screen S and maintains the same in its elevated position.

25 When the screen S is elevated the same surrounds the flame of the burner 11 so that the light rays emitted from the lantern are colored.

While I have hereinbefore stated that the 30 screen S is preferably red in color, it is to be understood that the screen may be of any selected color designed to exhibit a signal having a prescribed meaning.

When the screen S is at the limit of its 35 downward movement the flame of the burner 11 is unobstructed thereby so that the rays emitted from the lantern will be of the color of the globe or chimney G and which globe or chimney is preferably clear in order 40 to produce what is known as a "white light."

From the foregoing description, it is thought to be obvious that a lantern constructed in accordance with my invention is 45 particularly well adapted for use by reason of the convenience and facility with which it may be assembled and operated, and it will also be obvious that my invention is susceptible of some change and modification 50 without departing from the principles and spirit thereof, and for this reason I do not wash to be understood as limiting myself to the precise arrangement and formation of the several parts herein shown in carrying 55 out my invention in practice except as hereinafter claimed.

I claim:—

1. A lantern of the class described comprising a frame, a base supported thereby 60 and having its opposite ends open, the lower end of the base being defined by an inwardly directed flange, a reservoir insertible within the base through the upper end thereof and of a major diameter less than the mean 65 diameter of the base, the lower end portion

of the reservoir being extended for contact with the inwardly directed flange of the base, an annular member slidably arranged within the base and surrounding the reservoir, an expandable spring secured at one 70 end to the member and having its opposite end portion engaging the extended portion of the reservoir, said spring encircling the reservoir, a burner coacting with the reservoir, a screen engaged with the annular member and surrounding the burner when the member is at the limit of its movement in one direction, said spring coacting with the extended portion of the reservoir for holding said reservoir in applied position 80 within the base and means carried by the member and coacting with the base for limiting the movements thereof.

2. A lantern of the class described comprising a frame, a base supported thereby 85 and having its opposite ends open, the lower end of the base being defined by an inwardly directed flange, a reservoir insertible within the base through the upper end thereof and of a major diameter less than the mean 90 diameter of the base, the lower end portion of the reservoir being extended for contact with the inwardly directed flange of the base, an annular member slidably arranged within the base and surrounding the reservoir, an expandable spring secured at one 95 end to the member and having its opposite end portion engaging the extended portion of the reservoir, said spring encircling the reservoir, a burner coacting with the reservoir, a screen engaged with the annular member and surrounding the burner when the member is at the limit of its movement in one direction, said spring coacting with the extended portion of the reservoir for holding said reservoir in applied position 100 within the base and means carried by the member and coacting with the base for limiting the movements thereof, said means also coacting with the base for holding the member against movement.

3. A lantern of the class described comprising a frame, a base supported thereby 115 and having its opposite ends open, the lower end of the base being defined by an inwardly directed flange, a reservoir insertible within the base through the upper end thereof and of a major diameter less than the mean diameter of the base, the lower end portion of the reservoir being extended for contact 120 with the inwardly directed flange of the base, an annular member slidably arranged within the base and surrounding the reservoir, an expandable spring secured at one end to the member and having its opposite 125 end portion engaging the extended portions of the reservoir, said spring encircling the reservoir, a burner coacting with the reservoir, a screen engaged with the annular member and surrounding the burner when 130

the member is at the limit of its movement in one direction, and means carried by the member and coacting with the base for limiting the movements thereof, the extended portion of the reservoir being provided with openings.

4. A lantern of the class described comprising a frame, a base supported thereby and having its opposite ends open, the lower end of the base being defined by an inwardly directed flange, a reservoir insertible within the base through the upper end thereof and of a major diameter less than the mean diameter of the base, the lower end portion of the reservoir being extended for contact with the inwardly directed flange of the base, an annular member slidably arranged within the base and surrounding the reservoir, an expansible spring secured at one end to the member and having its opposite end portion engaging the extended portions of the reservoir, said spring encircling the reservoir, a burner coacting with the reservoir, a screen engaged with the annular member and surrounding the burner when the member is at the limit of its movement in one direction, and means carried by the member and coacting with the base for lim-

iting the movements thereof, the side walls of the reservoir having vertical corrugations, the extended portion of the reservoir being provided with openings adjacent the low points of the corrugations. 30

5. A lantern of the class described comprising a frame, a base supported thereby 35 and having its opposite ends open, the lower portion of the base being defined by an inwardly directed flange, a reservoir insertible within the base through the upper end thereof and of a major diameter less than the 40 mean diameter of the base, the lower end portion of the reservoir being extended for contact with the inwardly directed flange of the base, the side walls of the reservoir having vertical corrugations, the extended portion 45 of the reservoir being provided with openings adjacent the low points of the corrugations, and a burner coacting with the reservoir.

In testimony whereof I hereunto affix my 50 signature in the presence of two witnesses.

CLAY H. ESTES.
